UNITED STATES PATENT OFFICE.

JOHN ZIPP AND JOHN P. MORBACH, OF CLEVELAND, OHIO.

DESIGN FOR A SCOREBOARD.

55,499.

Specification for Design.

Patented June 15, 1920.

Application filed March 31, 1920. Serial No. 370,341. Term of patent 14 years.

To all whom it may concern:

Be it known that we, JOHN ZIPP and JOHN P. MORBACH, citizens of the United States, residing at Cleveland, in the county of Cuyahoga and State of Ohio, have invented a new, original, and ornamental Design for a Scoreboard, of which the following is a specification, reference being had to the accompanying drawing, forming part thereof.

The figure is a plan view of a scoreboard, showing our new design.

We claim:

The ornamental design for a scoreboard, as shown.

JOHN ZIPP.
JOHN P. MORBACH.
